UNITED STATES PATENT OFFICE.

JAMES A. HERRICK, OF NEW YORK, N. Y.

GAS-PRODUCER.

1,075,566.

Specification of Letters Patent.

Patented Oct. 14, 1913.

Original application filed July 10, 1911, Serial No. 637,615. Divided and this application filed August 7, 1911. Serial No. 642,622.

To all whom it may concern:

Be it known that I, JAMES A. HERRICK, residing at New York, in the county of New York and State of New York, have invented certain new and useful Improvements in Gas-Producers, of which the following is a specification.

This invention relates to the manufacture of producer gas, and more particularly to a new and improved mechanically operated gas producer, the present application being a division of my co-pending application, Serial No. 637,615, filed July 10, 1911.

One of the objects of the invention is to provide improved means for stirring the mass within the producer.

Another object is to provide improved means whereby the inner wall of the producer may be kept free from such accumulations as might result from the caking of partly consumed fuel therein, or from clinkers which might tend to adhere to the wall, thereby interfering with the effective operation of the producer.

Another object is to provide poking devices which may be inserted or removed from the producer at will.

Other objects will be in part obvious, and in part pointed out hereinafter.

The invention accordingly consists in the features of construction, combinations of elements and arrangements of parts, which will be exemplified in the construction hereinafter described, and the scope of the application of which will be indicated in the following claims.

In the accompanying drawings wherein is illustrated a preferred embodiment of my invention, Figure 1 is a view in vertical section showing the same; and Fig. 2 is a horizontal sectional view, taken substantially on the line 2-2 of Fig. 1.

Similar reference characters refer to similar parts throughout both figures of the drawing.

Referring now to the drawing, the producer proper is composed of a casing divided horizontally into two relatively movable sections denoted by the numerals 1 and 2, respectively. In the present instance the upper section 1 is stationary, and the lower section 2 is revolute. The upper section is supported by means of uprights 3, said uprights being provided with brackets 4, which are fixed to the casing 5 of the pro-

ducer. The lower section 2 is provided exteriorly with a ring member 6, which extends entirely thereabout intermediate its ends and is bolted to the casing 7. This ring member is rotatably supported upon 60 wheels 8 which are journaled in brackets 10 secured to the uprights 3. Section 2 may be revolved by means of a worm 11 which engages worm teeth 12 formed upon ring member 6.

The upper section 1, in the present instance, is provided with an annular curtain or partition 13 which divides said section into two chambers 14 and 15. Chamber 14 receives the fuel which is discharged into 70 the producer through a feeding device 16 and chamber 15 is a mixing chamber into which the gas passes before it is discharged from the producer through the delivery pipe shown in dotted lines at 17. The wall which 75 constitutes the partition 13 is supported by means of a metallic ring 18 which is fixed to casing 5 of section 1, said ring in the present instance being composed of a plurality of independent sections, one of which 80 is shown at 20 in Fig. 2. These sections are securely bolted together, so that the structure is substantially solid. The brick work of the upper section is supported upon this continuous ring like support. Each of the 85 members 20 which constitute the support 18 is formed with an aperture extending longitudinally thereof, in the present instance a pipe as at 21 being cast therein. The several pipes are then connected as by means 90 of bends 22, so that a continuous water circulating system is provided in ring like support 18, which tends to keep the same in a cool condition during the operation of the producer. I contemplate that this ring-support 95 may be cooled or ventilated in some other way than by water, and I use the word "ventilate" in the claims as well as the words "water-cooled" interchangeably, and contemplate any equivalent means or 100 method. It will be noted that each of the members 20 has an inwardly extending part 23, and that the wall 13 is arched as at 24, each arch spanning the space between the adjacent inwardly extending portions 105 23 of the members 20.

Formed in the cover portion 25 of the producer between the wall 13 and the outer wall of the producer is a sheathed aperture 26, said aperture being adapted to receive a re- 110

movable poker 27, said poker extending downwardly into the movable section 2 adjacent one of the inwardly extending portions 23 of the sections 20, as shown, so that during the rotation of section 2, the poker will be rigidly supported against lateral movement through its engagement with portion 23. The poker 27 is cooled as by means of a pipe 28 which extends downwardly therethrough, and terminates adjacent the lower end of the poker, the water discharged into the poker from pipe 28 being conducted therefrom as by means of a pipe 30 which is attached to the poker at its upper end. This poker may be removed from the producer by any suitable means, in the present instance a chain 31 being attached thereto as by means of a hanger 32. This chain may be secured to a block and tackle, if desired.

10 One of the sections 20 of the supporting member 18 is provided with an obliquely disposed aperture 33 which is adapted to receive a poker 34 which extends therethrough and into the interior of the movable section 2. This poker may also be readily removed from aperture 33 when desired. Poker 34 is cooled as by means of a pipe 35 which extends therein, and the water delivered into the poker from this pipe may be discharged by means of pipe 36. It will be noted that poker 27 is so located that the lower end is adjacent the inner surface of the wall thereof, so that during the rotation of section 2 any accumulations which may form upon the inner wall may be removed. The mass adjacent the outer edges of the mass may also be engaged by this poker and agitated during the rotation of said section 2. The poker 34 extends obliquely into the section 2 substantially to the central portion thereof to stir the mass during the rotation of said section.

15 20 25 30 35 40

I prefer to construct the lower section with a bottom slightly less than that of the upper section so that the latter will overhang the upper section, as shown in Fig. 1. The overhanging portion of section 1 is provided with a downwardly extending member 37 which enters a trough 38 carried by the lower section 2. Trough 38 is intended to be filled with water; the parts 37 and 38 thereby forming a water seal between the relatively movable portions of the producer. It will accordingly be seen that I have provided a construction particularly well adapted to attain, among others, all the aims and objects above set forth in a very efficient manner. The pokers operate to prevent the formation of crevices or fissures in the contained mass, thereby insuring the production of gas of even quality.

60 65 One important advantage inherent in the construction described herein is the fact that the various parts being removable, repair or replacement of any part burned out may be

accomplished with the expenditure of very little time and labor.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense. It is also to be understood that the language used in the following claims is intended to cover all of the generic and specific features of the invention herein described and all statements of the scope of the invention, which as a matter of language, might be said to fall therebetween.

Having thus described my invention, what I claim as new and desire to secure by Letters Patent, is:—

1. In a gas producer, in combination, a casing provided with a fixed upper section and a revoluble lower section, an annular chamber located in the upper section and spaced from the side walls thereof to provide a mixing chamber, said chamber being open at its lower end, a plurality of castings embedded in the wall of the upper section at the lower end thereof, said castings provided with horizontally spaced inwardly extending integrally formed members which support both walls of said chamber, means for connecting together said castings whereby a substantially continuous metallic ring is formed about the lower end of said upper section, and means for conducting water through all of said castings.

2. A gas producer comprising two independent concentric casings, one above the other and relatively rotatable, the upper casing having an interior lining from top to bottom thereof, said lining having an interior diameter less than that of the lower casing, so that said lining overhangs the interior of the lower casing, a metallic ring at the bottom of the lining for supporting the same, said supporting ring being carried at the lower end and interiorly of the upper casing, said lining and said ring providing a straight-away opening for a poker or the like wherein a poker or the like may be held rigid against lateral movement.

3. A gas producer comprising two independent concentric casings, one above the other, the upper casing having an interior lining from top to bottom thereof, said lining having an interior diameter less than that of the lower casing, so that said lining overhangs the interior of the lower casing, a cover extending over the upper casing and its lining, a metallic ring at the bottom of the lining for supporting the same, said supporting ring being carried at the lower end and interiorly of the upper casing, said cover, said lining, and said ring providing a

straight-away opening wherein a poker or the like may be held rigid against lateral movement.

4. A gas producer comprising a casing having a cover portion, and a hollow lining of refractory material supported interiorly of the casing, said hollow lining having an opening at its lower end to the interior of the casing and an opening to the exterior of the casing, and a ventilated support for said hollow lining, having portions beneath both walls of said lining and leaving the opening into the chamber substantially unobstructed, said lining and said ring being further provided with registering openings through which a poker may be inserted.

5. A gas producer comprising two independent concentric sections one above the other and relatively rotatable, the upper section having a mounting for a poker in one of its walls, and said upper section having at its lower end a metallic member extending inwardly and providing an aperture in registry with said poker mounting, whereby a poker may be inserted through the said mounting and through the opening in said inwardly extending member and down into the lower section and held rigid against lateral movement.

6. A gas producer comprising two inde-

pendent concentric sections one above the other and relatively rotatable, the upper section having a mounting for a poker in one of its walls, and said upper section having at its lower end a metallic member extending 35 inwardly and providing an aperture in registry with said poker mounting, whereby a poker may be inserted through the said mounting and through the opening in said inwardly extending member and down into 40 the lower section and held rigid against lateral movement, said inwardly extending member being ventilated.

7. A gas producer comprising a casing, a structure of refractory material lining the 45 inner wall of the casing at its upper end, supporting means for said structure disposed about the inner wall of the casing, said supporting means comprising a plurality of segmental metallic members united 50 into a continuous ring and having tortuous passages therethrough, and pipes connecting together the adjacent ends of the passages in contiguous members.

In testimony whereof I affix my signature 55 in the presence of two witnesses.
